CLAIM

The ornamental design for a roofing tool, as shown and described.

DESCRIPTION

FIG. 1 is a top perspective view of a roofing tool in accordance with my design;

FIG. 2 is a bottom perspective view thereof;

FIG. 3 is a top plan view thereof;

FIG. 4 is a bottom plan view thereof;

FIG. 5 is a first end elevation view thereof;

FIG. 6 is a second end elevation view thereof;

FIG. 7 is a first side elevation view thereof; and,

FIG. 8 is a second side elevation view thereof.

The broken lines illustrate portions of the roofing tool which form no part of the claimed design.
